PNEUMATIC DISPATCH SYSTEM

Frank J. Blume, Chicago, Ill.

Application February 16, 1942, Serial No. 431,045

7 Claims. (Cl. 243—16)

This invention relates to quickly passing or transferring messages or parcels from place to place as is necessary in industrial plants and stores; in industrial plants it becomes necessary to send messages from one department to another and to be able to send such messages from any of the several stations or departments to any other station as desired. This invention in its simplest form may be used in retail stores where the sales clerks at the several counters always are required to send the sales check and the cash to the cashier's office which is often located on the balcony. This invention is designed to greatly improve the transmitting of messages of any character from one place to another. The objects of this invention are to transmit parcels from place to place in a very expeditious manner; to enable the selection of the station to which a parcel should be delivered; to employ both air under vacuum pressure and electricity to accomplish the desired results; to employ a single tube to send and receive a parcel; to employ an electrically operated switch at each station to unlock the exit door at the station; to provide each carrier with mechanism which will register with other mechanism at its particular station to unlock the exit door; to enable the changing of the mechanism on any carrier so it will register with the mechanism at the station to which the carrier is intended to be delivered; to provide the inlet of the tube at each station with mechanism to insure the proper insertion of the carrier; to provide an exit door lock at each station which will only be unlocked by the carrier which was intended to be delivered at that particular station; and other objects to become apparent from the description to follow.

To describe the invention so that others versed in the art to which it pertains can make and use the same, it is illustrated on the accompanying three sheets of drawings forming a part of this specification, in which Figure 1 is a longitudinal sectional view through the tubing showing the construction at a station; Fig. 2 is a similar view of a part showing the exit door at a station unlocked; Fig. 3, is a sectional view showing a carrier about to enter the intake end of the tube; Fig. 4, is a sectional view on line 4—4 of Fig. 3; Fig. 5, is a diagrammatical view showing a plurality of stations connected on a single line of tubing; Fig. 6, is a diagrammatical view showing how one electrical contact on a carrier could be connected to any one of nine other electrical contacts on the same carrier; Fig. 7,

5 is a diagrammatical view showing how the carrier tube may be extended through each station before returning to the sending station; Fig. 8, is a similar view showing the carrier tube made endless and arranged so that a carrier may be sent from any of the numerous stations on the line to any other station on the line; Fig. 9, is a plan view of a carrier showing how the electrical contact spring can be changed from one position to another and Fig. 10, is a diagrammatical view showing how suction and pressure of air may be applied to the carrier tube.

Similar reference numerals refer to similar parts throughout the several views.

10 As seen in Fig. 1, the tube 10 enters the station from the right thence extends up a short distance where it is bent into a three-quarter circle 11, thence it extends down past the station exit door from whence it extends to the next station where it is again bent into an upwardly extending three-quarter circle as shown at 11. Each station is constructed similarly and therefore only one station is shown and will be described. Each carrier is constructed with the 15 hollow center portion 12 and the larger end portions 13 usually made of felt or some other soft material. One end of each carrier is made removable to permit placing some cash or other material inside the portion 12. Each carrier has 20 secured to it the two metal springs 14 which are electrically connected and are arranged to make electrical contact with the stationary shoes 15 near each station, rigidly secured to the tube 10 but electrically insulated from the tube 10. Each 25 shoe 15 is connected by a wire 16 to the coil of a solenoid 17, and a source of electric energy 18 is connected in one of the wires 16 so as to make a complete electric circuit from one shoe 15 to the other shoe 15. The metal springs 14 are 30 electrically connected by the wire 19 seen in Figs. 3 and 4. The core 20 of solenoid 17 is connected by rod 21 to an arm of the door catch 22, pivoted at 23 to a bracket rigid with tube 10. The catch 22 carries a sliding block 24 which 35 is by force of gravity normally tends to rest on the hook of catch 22. The exit door 25 is pivoted at 26 to the tube 10, and has at its free end the extending lip 27, which, when the door is locked rests on the hook of catch 22 as seen in Fig. 1. 40 When the proper carrier passes up in tube 10 just before entering the three-quarter circle 11 the metal springs 14 will contact the shoes 15 and close the electric circuit through the coil of solenoid 17 and cause a pull on rod 21, and 45 move the hook of the catch 22 from under the 50 hook of catch 22. The exit door 25 is pivoted at 26 to the tube 10, and has at its free end the extending lip 27, which, when the door is locked rests on the hook of catch 22 as seen in Fig. 1. 55

lip 27; this movement of catch 22 will permit the block 24 to drop by gravity onto the hook of catch 22, as seen in Fig. 2, thus preventing the catch 22 being moved to have its hook under the lip 27 of the door by the coiled spring 28. The door 25 is normally held up in a closed position by the air suction within the tube 10, and the light spring 29. Thus when said carrier has traveled around in the three-quarter circle 11 to about diametrically opposite the vertical portion of tube 10 it will drop down against the upper inclined surface of the door 25 and if, as was just described, the said door is unlocked the inertia of the carrier will open the door 25 downwardly, swinging the same on its pivot 26 and the carrier will drop into the basket 29 immediately below the door 25. The air suction and the spring 29 will move the door upward to a closed position. It will be noted that when the door returns to a closed position its lip 27 will contact the lower end of the sliding block 24 and lift same so that the hook of catch 22 will again come to rest under the lip 27 of the door 25, as seen in Fig. 1. The upper side of the door 25 is preferably made on an incline to direct the passing carriers downward on an angle into the tube 10.

In Fig. 3, is shown an enlarged view of a carrier and the open end of the tube 10, into which the carrier is about to be placed. It is important that the carrier be inserted into the tube 10 in the proper position and to this end each carrier is made with a depressed portion 29" at each end, but the front end of each carrier has an extension 30 positioned to contact the push pin 31, pivotally connected to the one arm of the bell crank lever 32, pivoted at 33, and which has pivoted to its other arm the sliding rod 34 extending down through a perforation in the barricade 35, which is pivoted at 36 to a frame 37 made rigid with the tube 10. The lower end of the sliding rod 34 is made to engage the shoulder 38 and lock the barricade 35 against swinging downward to the left into the pocket 39 provided therefor in the frame 37. A coiled contracting spring 40 yieldingly holds the sliding rod 34 down with its lower end in the path of the shoulder 38. A light spring 41 normally yieldingly holds the barricade 35 up in the path of a carrier being inserted into the tube 10. Thus if a carrier is presented to the entrance of tube 10 in an incorrect position, the barricade 35 will remain in a locked position and prevent the insertion of the carrier. Such a barricade 35 and its connections is provided at each station along the entire line of tubing 10' and in addition to such barricade at each station a closure door 41' is hinged to the end of the inlet branch 10' of the tube as seen in Figs. 1 and 2, to seal the tube against the entrance of any air.

In Fig. 5, is shown diagrammatically the tube 10 connecting eighteen stations and having its ends, both intake and discharge, at a location which might represent the cashier station in a retail store. A device for creating an air suction is shown at 42.

In Fig. 6, is shown diagrammatically the numerous combinations which can be provided on each of the carriers when ten electrical contacts are provided for the carriers in the system. It will be noted that the electrical contact 14 on the lower side of the carrier shown may be electrically connected with any of the other nine electric contacts on the carrier. Thus the next 75 is placed into the carrier, the carrier is placed

contact 14 (not shown) could be tied up with eight other contacts on the carrier and so on until the ninth contact 14 (not shown) is reached making in all forty-four different combinations for the carriers, in other words forty-four stations could be accommodated when ten contacts are on each carrier. More or less contacts could be provided on larger or smaller carriers.

10 In Fig. 7, is shown diagrammatically a system having a single tube 10", the return portion of the tube designated by 10" and arrows pointing to the right, passing through each station, where it is provided with an intake branch 10'" simply provided with a sealing cover 41' as is shown in Figs. 1 and 2. In a system of this construction it is not necessary to furnish a barricade 35 such as is shown in Fig. 3 because the returning carriers pass through return branch tube 10" having arrows pointing to the right and do not pass any station exit doors 25.

20 In Fig. 8, is shown diagrammatically a system having an endless tube 10""", the one branch passing through all the stations is provided with an exit door 25 at each station and the other branch passing through all the stations is provided with an intake branch 10"" at each station. Each intake branch 10"" is provided with a barricade 35 in the extension 37 and a sealing door 41' while an exit door 25 identical with the one shown in Figs. 1 and 2 is provided at each station. In the drawings in Fig. 8, four stations are indicated by the letters A, B, C and D, and with this arrangement of tubing it is possible to send a carrier from any one station to any one of the other stations by simply placing the one contact 14' on the carrier, see Fig. 9, to register with the shoes 15 at the station where it is desired to have the carrier delivered. Thus the carrier shown in Fig. 9, has the contact 14' set at the position indicated by C, which will cause the carrier to be discharged at the station indicated by C in Fig. 8. Thus the attendant at any of the stations A, B, C or D can deliver a message or parcel to any one of the said stations desired.

30 The carriers and tube are made of a form in cross section to prevent the carriers from rotating in the tube at any time, in the drawings they are shown oval in cross section.

40 In operation, referring to Figs. 1, 2 and 5, which illustrate a system designed for retail stores, each sales station is provided with one or more carriers, the carriers at any one station having the springs 14 made to co-operate with the contact shoes 15 at that particular station. The sales clerk places the sales check and money into the carrier and then proceeds to place the carrier into the tube branch 10' by opening the door 41' which is quickly closed by spring pressure in addition to the air suction. The carrier is drawn through the tube 10 by air suction caused by the air suction device 42 and finally is discharged into the basket 43 shown in Fig. 5. When the sales clerk opens the door 41' to insert the carrier into the tube 10' the air entering through said door opening will immediately cause all oncoming carriers, if there be any, to stop because there will be no suction of air in the tube 10 back of this point. Thus all interference of carriers traveling in tube 10 with any carrier being introduced into the tube 10 is avoided.

50 At the cashier station, after the proper change 70 is placed into the carrier, the carrier is placed

into the tube 10 seen in Fig. 3, and the air suction will draw it along in tube 10 until it reaches the station where its two contacts or metal springs 14 register with and contact the shoes 15; the contacting of the springs 14 with the shoes 15 will close the circuit from source of energy 18, coil of solenoid 17, wires 16 and back to source of energy 18. This as previously described will unlock the door 23 at that station and when the carrier descends and hits the door, the door will open and the carrier will fall into the basket 29. As the carrier passes other stations where the door 25 is not unlocked the carrier will descend and hit the inclined surface of the door and pass the station and continue traveling in tube 10. Thus many carriers are delivered to different stations by the use of a single pneumatic tube which greatly reduces the cost of installation and maintenance.

Referring to Fig. 7, which system is designed either for retail store service or industrial plant service, both ends of the tube 10" are open at a station to which all carriers are delivered and from which station all carriers are sent to the different stations along the line. A closure door 41' and a source of air suction 42 is connected to the receiving end of tube 10" and the other end of said tube 10" is provided with the regulation barrier 35 shown in Fig. 3, which is pivoted in the frame 37. In this system the return tube 10" coming from the farthest station on the line has an upward extension at each station where it is provided with an inlet branch 10'" and each such branch has a closure cover 41' as shown in Figs. 1 and 2. Since all the carriers from all the stations are returned to the sending out station through the return tube it is not necessary to have the barrier 35 with its frame 37 at all the outlying stations. Thus, on account of its cheapness, this system may be preferred in some industrial plants.

Referring to Fig. 8, which system is especially designed for industrial plants the tube 10"" is made endless with a source of air suction 42 placed along the line wherever convenient. An air-shutoff gate 44 is provided between the air outlet 45 and the air inlet 46 with the proper grating over each to prevent the carriers entering same. As shown the tube 10"" has the conventional semicircular portion 11 at each station, also the exit door 25. Another portion of the tube 10"" has the upturned portions 47 at each station provided with the intakes 10"" as described. If the attendant at station A desires to send a carrier to station D the attendant at station A sets the spring contact 14' to D on the carrier seen in Fig. 9, and deposits the carrier into the tube 10"". If the attendant at station D desires to send a carrier to station B the spring contact 14' is set to register with B on the carrier seen in Fig. 9, and so on.

Fig. 10, illustrates how a fan or source of air suction 42 may have its intake connected by tube 45 to the carrier transmitting tube 10 on one side of the damper 44 and its discharge end connected to the carrier transmitting tube 10 by tube 46 on the other side of the damper 44.

What is claimed and desired to be secured by Letters Patent of the United States is:

1. Mechanism for controlling the destination of carriers to any one of a plurality of receiving stations connected in a single dispatch tube line from any one of said stations, each station having a carrier discharge opening and a valve therefor arranged to be impacted by carriers in

transit and being operative when maintained in closed position under carrier impact to by-pass carriers through the station, comprising, in combination, means operatively related to each station for positively latching its valve in closed position, a normally deenergized control unit for each valve latching means adapted when energized to render said latching means ineffective and thereby condition said valve for opening movement under carrier impact, means on the carrier in transit for energizing only its co-operating station valve control unit, and an inclined upward extension on each station valve against which all passing carriers impact and which serves to deflect the impacting carrier into the tube line.

2. Mechanism for controlling from any one station the destination of carriers to any one of a plurality of stations connected in a single dispatch tube line, each station having a carrier discharge opening and a valve closing said opening and arranged to be impacted by carriers in transit, comprising, in combination, latching means associated with each of said stations for maintaining the valve thereof in closed position, each said means including a latch carried by the tube line and a floating block normally interlocked therewith, said block being movable by gravity upon the latch being moved to free the valve for opening, a normally deenergized control unit operatively related to said latching means adapted when energized to render said latching means ineffective, thereby to condition the unlatched valve for opening under impact of the carrier, and operable means at each station for energizing any one of said control units.

3. Mechanism for controlling the destination of carriers to any one of a plurality of stations connected in a single dispatch tube line, each station having a carrier discharge opening and a valve having an inclined impacting surface therefore arranged to be impacted by carriers in transit and being operative when maintained in closed position under carrier impact to by-pass carriers through the station, comprising, in combination, means operatively related to each station for positively latching its valve in closed position, an electrical control for each valve including a solenoid adapted when energized to render said latching means ineffective, thereby to condition said valve for opening under carrier impact, a normally open switch in series with said solenoid, means for closing said switch in response to the approach of a carrier intended to be discharged at the station, such carrier having its electric contacts to operate the solenoid circuit in its station arranged in proper relation to one end of the carrier, and a pivoted baffle locked against movement at each entrance to the tube line, which baffle can only be unlocked for movement by the presentation of the proper end of each carrier to the entrance.

4. In a pneumatic dispatch tube system, the combination of a dispatch tube line, a plurality of stations connected therein in series relation, each station having a carrier discharge opening and a valve therefor normally in its closed position and said valve being provided with an inclined surface which is impacted by carriers in transit, comprising normally operative valve latching means associated with each of the stations for maintaining the valve thereof closed under carrier impact, said latching means including a latching member pivoted on the dispatch tube line, said inclined surface of the valve

when contacted by the carrier impacting same will direct the carrier through the station into the line.

5. In a pneumatic dispatch tube system, the combination of a dispatch tube line, a plurality of stations connected therein in series relation, each station having a carrier discharge opening controlled by an electric circuit closed by contacts on the passing carrier and a carrier inserting opening, each inserting opening provided with a barricade having a push pin so constructed and arranged that a carrier can be inserted only when presented with the proper end to have the electric contacts on same properly presented at the station.

6. In a pneumatic dispatch tube system, the combination of a dispatch tube line, a plurality of stations connected therein in series relation, each station comprising a carrier discharge opening controlled by an electric circuit closed by contacts on the carrier and a carrier inserting opening, each inserting opening constructed with a barrier mounted on a pivot carried on the tube

line structure and biased to a position to obstruct the free passage of a carrier, a catch to prevent the moving of the barrier from its obstructing position actuated by the proper end of each carrier to actuate said catch to release said barrier for movement out of the path of the carrier presented to the inserting opening.

7. In a pneumatic dispatch tube system, the combination of a dispatch tube line, a plurality of stations connected therein in series relation, a plurality of carriers having electric contacts properly arranged with relation to one end of the carrier, each station comprising a carrier discharge opening and a carrier inserting opening, each inserting opening constructed with a barrier to prevent the improper insertion of a carrier and a lock to prevent moving the barrier out of its obstructing position, and an element on one end of each carrier to move said lock on the barrier to enable moving the barrier out of its obstructing position.

FRANK J. BLUME.
